(57) CLAIM

The ornamental design for a storage wallet for compact discs with external storage capacity, shown and described.

DESCRIPTION

FIG. 1 is a front perspective view of a storage wallet for compact discs with external storage capacity, showing our new design; the broken lines showing discs, and a fastenerpull throughout the views representing portions of the design that form no part of the claim;

FIG. 2 is a top plan view of the invention illustrated in FIG.
1.

FIG. 3 is a front elevation view of the invention shown in
FIG. 1;

FIG. 4 is a left elevation view of the invention illustrated in
FIG. 1;

FIG. 5 is a rear elevation view of the invention illustrated in
FIG. 1;

FIG. 6 is a left elevation view of the invention illustrated in
FIG. 1;

FIG. 7 is a bottom plan view of the invention illustrated in FIG. 1; and,

FIG. 8 is a front perspective view thereof shown in an open position. The broken lines depicting interior leaves representing portions of the design that form no part of the claim.
